Patent expires March 11, 1964

7 Claims. (Cl. 250—27.5)

1

This invention relates to an electric discharge tube comprising an anode cooled artificially, a gas-absorbing material such, for example, as zirconium, thorium, titanium or tantalum being provided inside the tube.

It is known to utilize these materials as a getter in electric discharge tubes, more particularly in transmitting tubes, and to apply such materials at several points. In this case the problem is involved that the materials must have a comparatively high temperature; also during the operation of the tube, in order permanently to obtain a satisfactory gas-absorbing action. It has previously been suggested for this purpose either to apply zirconium to grids or anodes, or to arrange zirconium so as to be in contact with the cathode. The application of zirconium to grids may lead to the secondary grid-emission being strongly suppressed and this is undesirable in definite cases; since more particularly in the case of transmitting tubes a certain secondary grid-emission is necessary for the suppression of the grid current. The arrangement of zirconium or a similar metal having a satisfactory gas-absorbing capacity in contact with the cathode may in definite cases involve the drawback that the metal does not attain a temperature sufficiently high for the absorption of all the residual gases and, in addition, cannot be utilized in tubes of the modern type.

As a rule, the application of zirconium to the anode yields satisfactory results. In definite cases, however, more particularly when the gas-absorbing material is applied to an anode cooled artificially, the difficulty is involved that, as before, the temperature required for a satisfactory absorption of gas is not attained. In addition, it is not a simple matter to apply the zirconium thoroughly to such an anode which, as a rule, consists of copper, since for the fastening by sintering comparatively high temperatures are required with the result that the copper anode is deteriorated. Consequently, in those cases in which in practice the fastening of the powdery metal by sintering was abandoned, this metal frequently fell off from the anode during operation.

According to the invention, the above-described drawbacks are fully avoided by that in an electric discharge tube comprising an anode cooled artificially, a body of refractory material, covered with a gas-absorbing metal, such as zirconium, thorium, tantalum, titanium or a similar material is fastened to the anode so as to be in incomplete heat-conductive contact with it.

2

When using this construction, the zirconium may be heated to a sufficiently high temperature by electronic bombardment. This high temperature constitutes in this case only an advantage and cannot do any harm since the carrier body is not in contact with the glass parts of the tube. In fact, the fastening of this body to the anode, cooled artificially, so as to be in incomplete heat-conductive contact with it yields a satisfactory solution for the fastening of this body and at the same time for the heating and also for the dissipation of heat, while the gas-absorbing metal may be thoroughly fastened by soldering to this body beforehand.

As a material for the carrier body use is preferably made of molybdenum, tungsten, or a similar refractory metal. This body, before being secured to the anode, is covered in a known manner with zirconium or a similar gas-absorbing metal, which is sintered on it at high temperature.

It will be clear from the foregoing what is to be understood by the term "incomplete heat-conductive contact." This refers to a contact such that the body acquires a sufficiently high temperature whilst avoiding, on the other hand excessive heating by means of appropriate contact with the cooled anode which, as a rule, is also an electric contact. It depends on circumstances when these conditions are fulfilled. As a rule, however, an incomplete heat-conductive contact exists when the anode and the carrier body for the gas-absorbing material are in contact with each other but do not make contact through a large portion of their surfaces, the contact points being formed by means of operations as soldering, welding and the like. The form and the fastening of the said body frequently depend on the shape of the anode. In a particular form of construction of a tube according to the invention, the carrier for the gas-absorbing metal is constituted by a cylinder which surrounds the anode or is fastened inside the latter. This fastening may be effected, for example, by starting from a split cylinder and by depressing the latter at some points and subsequently clamping it around or inside the anode, so that contact between the two objects exists only at the points depressed. The zirconized body may alternatively have the shape of a helix or a spiral clamped around or inside the anode, it being possible for the anode to be provided with grooves in order to make the helix contact at a few points only. Furthermore, use may be made of rods covered with gas-absorbing material,

which are laid into grooves of the anode and are clamped on the latter, for example, by means of some turns of zirconium wire.

In order that the invention may be clearly understood and readily carried into effect, it will now be described more fully with reference to the accompanying drawing.

Fig. 1 shows a tube according to the invention.

Fig. 2 shows a detail of the tube of Fig. 1.

Fig. 3 shows a detail of an anode comprising grooves.

Fig. 4 is a helical body covered with gas-absorbing material, and

Fig. 5 shows a particular form of construction of a tube according to the invention, i. e. of a so-called transit-time tube.

Figure 6 shows a rod shaped body covered with gas-absorbing material, said body being positioned in the grooves of the anode.

In Fig. 1, reference 1 indicates the cylindrical anode cooled artificially, which may be cooled by means of a liquid supplied through the tube 2. The anode 1 is sealed to the wall 3 which may be of metal or glass of the tube and constitutes itself also a portion of the wall. The anode is surrounded by a grid 4 and a cathode 5. A split cylinder 6 of molybdenum, superficially covered with zirconium, is clamped around the anode 1. The cylinder is depressed at some points 7, as is shown clearly in Fig. 2, so that heat-conductive contact between the cylinder 6 and the anode 1 exists only at these points.

Instead of with depressed portions of the cylinder 6, satisfactory results may also be obtained by clamping a smooth split cylinder 10 (Fig. 3) around an anode 8 comprising grooves 9.

Fig. 4 shows a helical zirconised body which may be fastened in an anode which, if desired, may comprise grooves of opposite direction of winding.

Fig. 5 shows a portion of a so-called transit-time tube in which the electrons in the form of a beam run to the anode 15. During the covering of the distance from cathode to anode, the velocity of the electrons is modified, the construction being such that the rapid electrons are enabled to overtake the slow ones. Tubes of this kind operate at very high frequencies and high voltages, resulting in a strong heating of the anode 15 at that point at which the electron beam impinges on the anode. If the beaming is maintained to the end of the anode, the portion 16 of the anode 15 will be heated very strongly, so that cooling by liquid is necessary. Consequently, the anode will retain a comparatively low temperature and this is necessary in view of the glass seal in the wall 12. Now, the invention is applicable to a tube of this kind, as is shown in Fig. 5. Inside the anode 15 is arranged a split molybdenum cylinder 13 covered with a gas-absorbing material. As in the above-described form of construction, this cylinder may comprise depressed points. If desired, the anode may in part be turned out, so that the cylinder is enclosed and is prevented from being displaced or falling out of the anode. The wall 12 of the tube is surrounded by a magnet

coil 14 and by means of a displacement of this coil the electron paths may be so influenced that the electrons inside the anode cylinder are more or less divergent, so that the electrons impinge on the cylinder 13 to a greater or less extent. The temperature and hence the gas-absorbing action of the zirconium can thus be controlled in a simple manner. The divergence is preferably controlled in such a manner that the cylinder 13 is red-hot during the operation of the tube.

Figure 6 shows a helical rod shaped body 17, coated with a gas-absorbing material such as zirconium, and positioned in the grooves of an anode, 18.

Although only a few forms of construction have been described, it is evident that the invention is realizable in many other ways.

What I claim is:

1. An electric discharge tube comprising an artificially cooled anode electrode, a body of refractory material in poor thermal contact with said anode electrode, and a gas-absorbing metal sintered to said refractory body.

2. An electric discharge tube as claimed in claim 1, wherein a refractory body covered with a gas-absorbing metal is secured to a copper anode, said anode being cooled artificially and being in heat-conductive contact with said refractory body at a few points only.

3. An electric discharge tube as claimed in claim 2, wherein the body covered with the gas-absorbing metal has the shape of a split cylinder depressed at some points.

4. An electric discharge tube as claimed in claim 1, wherein the anode is provided with grooves, and the refractory body covered with the gas-absorbing metal is in heat-conductive contact with the projecting surface of the anode.

5. An electric discharge tube comprising an artificially cooled anode, a body of refractory material in poor thermal contact with said anode, and zirconium metal sintered to said refractory body.

6. An electric discharge tube comprising an artificially cooled anode, a body of refractory material in poor thermal contact with said anode, and titanium metal sintered to said refractory body.

7. An electric discharge tube comprising an artificially cooled anode, a body of refractory material in poor thermal contact with said anode, and tantalum metal sintered to said refractory body.

EDUARD GERARDUS DORGELO.
